(57) **CLAIM**

The new and ornamental design for a lighted knife handle, as shown and described.

DESCRIPTION

FIG. 1 is a perspective view of a first embodiment of the lighted knife handle of the present invention, the knife blade depicted in broken lines and not forming a part of the claimed design;

FIG. 2 is a top plan view of FIG. 1;

FIG. 3 is a side elevational view of FIG. 1, with the opposite side being a mirror image;

FIG. 4 is a bottom plan view of FIG. 1;

FIG. 5 is a rear end elevational view of FIG. 1;

FIG. 6 is a front end elevational view of FIG. 1;

FIG. 7 is a perspective view of a second embodiment of the lighted knife handle of the present invention, the knife blade depicted in broken lines and not forming a part of the claimed design;

FIG. 8 is a top plan view of FIG. 7;

FIG. 9 is a side elevational view of FIG. 7, with the opposite side being a mirror image;

FIG. 10 is a bottom plan view of FIG. 7;

FIG. 11 is a rear end elevational view of FIG. 7; and,

FIG. 12 is a front end elevational view of FIG. 7.
